(57) **CLAIM**

The ornamental design for a dock for respiratory sensing devices as shown and described.

DESCRIPTION

FIG. 1 is a perspective view showing a dock for respiratory sensing devices;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the dock for respiratory sensing devices of FIG. 1 in use with respiratory sensing devices.

The appearance of any portion between the break lines forms no part of the claimed design.

The broken lines depict portions of the dock for respiratory sensing devices that form no part of the claimed design.

1 Claim, 6 Drawing Sheets
